CLAIM

The ornamental design for a paper product, as shown and described.

DESCRIPTION

FIG. 1 is a top plan view of a paper product showing a paper product, such as a sheet of a paper towel or tissue. A specific length and width of the product forms no part of the claimed design; and,

FIG. 2 is an enlarged top plan view of one repeat unit of the paper product of FIG. 1, it being understood that the outer perimeter of FIG. 2 depicts the boundaries of one repeat unit of the claimed design. The design repeats uniformly throughout the length and width of the paper product.

The broken lines in the drawings form no part of the claim.
